HAIRBRUSH

John G. Baumgartner, Aurora, Ill.

Filed Oct. 20, 1959, Ser. No. 57,997

Term of patent 14 years

(Cl. D86—10)

I claim:

The ornamental design for a hairbrush, as shown.
